UNITED STATES PATENT OFFICE.

WILLIAM SMITH PACA, OF BALTIMORE, MARYLAND, ASSIGNOR TO THE
EASTERN ELECTRIC COMPANY, OF SAME PLACE.

ELECTRIC ANNUNCIATOR-CALL.

SPECIFICATION forming part of Letters Patent No. 426,307, dated April 22, 1890.

Application filed November 27, 1889. Serial No. 331,801. (No model.)

To all whom it may concern:

Be it known that I, WILLIAM SMITH PACA, of the city of Baltimore, and State of Maryland, have invented certain Improvements in Electric Calls, of which the following is a specification.

In buildings where a system of speaking-tubes is employed and arranged so that communication may be had from one room with all the others the mouth-pieces are each provided with a whistle, and in calling one room the whistles of all the others are sounded. To prevent confusion, a peculiar call is sometimes adopted for each room or floor, but notwithstanding this expedient all the whistles are sounded, and no privacy can be maintained in transmitting messages, as each room is notified by sound that a communication is about to be made and it is only necessary for any one to place his ear to any mouth-piece to ascertain its character.

The principal object of my invention is to arrange a system of calls so that an alarm is sounded only in the apartment with which communication is sought; and the invention consists in placing in each room or apartment a magneto-bell and a switch-board in an open circuit, having points connected by wires to the call-boxes in all the other rooms, and a switch-strap which may be made to form a connection between the magneto-bell in any other room and the point on the switch-board which represents it, as will hereinafter fully appear.

In the further description of the said invention which follows reference is made to the accompanying drawings, forming a part hereof, and in which—

Figure 1 is a sectional elevation of a building with four rooms or floors to which my invention is applied. Fig. 2 is a rear view of one of the call-boxes with the back thereof removed and shown on an enlarged scale.

In the said drawings, A, B, C, and D represent the rooms or floors of the building, and E, F, G, and H call-boxes in the respective rooms, each containing a magneto-bell.

I, J, K, and L are switch-boards in the various rooms. A wire a leads from one connection of each magneto-bell to the switch-strap M of its switch-board, and another wire

b leads from the other connection of the bell or ringer to a point representing the room or floor on all the switch-boards in the building or system except its own. A third wire c constitutes the return-circuit wire to which all the calls are connected.

Room 1 has on its switch-board points marked 2, 3, and 4. Room 2 has its switch-board provided with the points 1, 3, and 4, and so on, each switch-board having a point numbered to represent each room or floor except the one in which it is situated.

Referring to Fig. 2, which, as before stated, is a rear view of one of the boxes with the back thereof removed, N is the generator, which is of the usual type, and O represents the ringing coils and magnets. The three posts to which the wires a, b, and c are attached are respectively denoted by d, e, and f. One connection of the generator runs to the post d and the other to the post f. The post e unites with one connection of the ringing coils, and the other connection taps the generator-wire at g.

From the foregoing it will be understood that all the call-boxes are in a normally-open circuit, and that the closing of the circuit for any room affects only the call-box in that room which is sounded.

As only one call is sounded by moving a switch-strap to contact with a point on the switch-board, lower-resistance coils may be employed in the call-boxes than if several were rung, and the construction of the call-boxes is thereby cheapened.

R is a speaking-tube having the branches h, i, j, and k and mouth-pieces l, m, n, and o opening into the various rooms.

The operation of the invention is as follows: Supposing a person in room 1 wishes to communicate with another in room 4, he turns the switch-strap so that its end comes directly over the point 4, and then presses it in to close the circuit in which the ringing mechanism in room 4 only is included. He then turns the handle p, which causes the magneto-bell in room 4 to sound. Upon hearing the call the person in room 4 applies his ear to the mouth-piece of the speaking-tube and receives the communication.

The operation of calling from room 4 to

room 1, or from any room to another, is the same as that described, the summoner in all cases connecting his switch-strap with a point bearing a number corresponding with the 5 room with which he desires to communicate.

While I have illustrated my invention by introducing a speaking-tube as the means of communication between the various rooms, I do not limit myself to its use, as a telephone 10 or telegraph instrument could be employed instead; or the system of calls, as described, could be used in connection with a dumb-waiter having openings at the several floors or rooms.

15 I claim as my invention—

A system of calls, which consists of a series of magneto-bells, a series of generators, and a series of switch-boards, one of each series being in separated rooms, each generator having a wire leading therefrom to the switch-trap of the switch-board in the same room, each magneto bell having a wire connecting it to all the switch-straps except that in the same room, and a wire forming a common return-circuit and connecting all the generators 25 and bells, substantially as specified.

WILLIAM SMITH PACA.
